[57] CLAIM

The ornamental design for a stationery accessory, as shown and described.

DESCRIPTION

FIG. 1 is a right front perspective view of a stationery accessory showing my new design in a closed condition;

FIG. 2 is a right front perspective view of FIG. 1 in an opened position;

FIG. 3 is a front elevational view in the closed position;

FIG. 4 is a front elevational view in the opened position;

FIG. 5 is a rear elevational view in the closed position;

FIG. 6 is a rear elevational view in the opened position;

FIG. 7 is a right side elevational view in the closed position;

FIG. 8 is a right side elevational view in the opened position;

FIG. 9 is a left side elevational view in the closed position;

FIG. 10 is a left side elevational view in the opened position;

FIG. 11 is a top plan view in the closed position;

FIG. 12 is a top plan view in the opened position;

FIG. 13 is a bottom plan view in the closed position;

FIG. 14 is a bottom plan view in the opened position;

FIG. 15 is a right front perspective view of a second embodiment of my new design of FIG. 1 in a closed condition;

FIG. 16 is a right front perspective view of FIG. 15 in an opened position;

FIG. 17 is a front elevational view of FIG. 15 in the closed position;

FIG. 18 is a front elevational view of FIG. 15 in the opened position;

FIG. 19 is a rear elevational view of FIG. 15 in the closed position;

FIG. 20 is a rear elevational view of FIG. 15 in the opened position;

FIG. 21 is a right side elevational view of FIG. 15 in the closed position;

FIG. 22 is a right side elevational view of FIG. 15 in the opened position;

FIG. 23 is a left side elevational view of FIG. 15; in the closed position;

FIG. 24 is a left left elevational view of FIG. 15; in the opened position;

FIG. 25 is a top plan view of FIG. 15 in the closed position;

FIG. 26 is a top plan view of FIG. 15 in the opened position;

FIG. 27 is a bottom plan view of FIG. 15 in the closed position; and,

FIG. 28 is a bottom plan view of FIG. 15 in the opened position.
